UNITED STATES PATENT OFFICE.

GLEN N. HUTCHINSON, OF MONTCLAIR, NEW JERSEY, AND GUY S. CARDEN, OF ENDICOTT, NEW YORK, ASSIGNORS TO INTERNATIONAL TIME RECORDING COMPANY OF NEW YORK, OF ENDICOTT, NEW YORK, A CORPORATION OF NEW YORK.

NIBBLING MACHINE.

Application filed January 6, 1925. Serial No. 780.

This invention relates to nibbling machines, adopted to cut their way through metal sheets by a series of punchings; each punching operation cutting away a small piece of metal.

5 In machines of this character as in other metal-punching machines, the metal being worked upon is placed on a supporting table or bed plate, flush with which is a die. Above the die is the punch which reciprocates up and down, reaching into the die on each downward strike. The work is fed slowly over the die, and the punch in cooperation with the die, shears off chips. Inasmuch as the work is performed on one side only of the punch, there 15 is a constant tendency for the punch to be pushed back out of alignment with the die, and frequently, the rear edge of the punch strikes the rear edge of the die. This causes the punch to break, and often also destroys 20 the die.

One of the objects of the present invention is to overcome this fault, by devising a punch that will be positively guided into the die, so that it cannot be forced over the edge thereof.

25 These machines are also provided with a stripper for preventing the metal being cut from being lifted by the punch. This stripper is adjustable up and down, as is also the punch holder. Workmen frequently adjust 30 the punch holder to adjust the stroke of the punch, without adjusting the stripper accordingly. If the punch holder is lowered, without lowering the stripper, the holder, when the machine starts to operate, strikes the top 35 of the stripper and breaks it off.

Another object of the invention is to devise a stripper that cannot be broken or otherwise damaged when the operator fails to properly adjust it.

40 Referring to the drawings wherein we have shown what we now consider to be the preferred form of our invention:

Fig. 1 is a side elevation of the upper position of a nibbling machine, partly in section.

45 Fig. 2 is a front elevation of the same portion of the machine, partly in section.

Fig. 3 is a section taken on line 3—3 of Fig. 2.

Fig. 4 is a detail of the punch and die.

50 In the drawings, the table or bed plate is shown at 1, fastened by bolt 2 to the block 3 which is in turn fastened by bolts 4 to the bed 5 of the machine. The die 6 is held in

position in the block 3. The overhanging arm 7 carries the punch holder 8, adjustably fastened by screw threads to a plunger 9, 55 adapted to be reciprocated up and down by a drive shaft 10. The drive forms no part of the present invention, and is therefore not shown here. The punch 11 is fastened in a 60 bushing 12 in the holder 8. The punch extends downwardly as at 13 (Fig. 4) below its cutting edge 14, and the back surface thereof engages the rear interior of the die. The depending portion 13 of the punch may be long 65 enough so as not to rise entirely out of the die when the punch is in its raised position, or if it is permitted to rise out of the die, it should at least be long enough to enter the die before the cutting shoulder 14 reaches the metal 70 which is being cut. This cooperation between the punch and die while the cutting or punching is being done, serves to guide the punch, and prevents it from working back or being pushed back to strike the edge of the die. The 75 sheet 15 of metal may be pushed against the forward part of the depending portion 13 of the punch which will thus act as a guide in feeding the sheet to the machine.

The stripper is shown in the form of an inverted cap 16, having threaded engagement with the inner circumference of a bushing 17. The lower part of the arm 7 is bored slightly larger than its main interior diameter, to receive the bushing 17. Reaching into this portion of the bore are spring-pressed steel balls 18, contained in the walls of the bore. The holes through which the balls reach are smaller toward the inside or toward the bore than the diameter of the balls, so that the latter cannot fall through. The outer circumference of the bushing 17 is provided with a circumferential groove 19 and numerous vertical flutings 20. Thus, when the bushing 17 is slipped into place, the balls 18 will engage 85 it in the groove 19 and hold it up in position. The balls will also nestle in the flutings 20 and prevent jarring of the machine from causing the bushing to turn. The stripper 16 has an arm 21 rigidly fixed thereto, reaching 90 into a groove 22 in a member 23, supported for up and down adjustment in arm 7. The screw 24 is adapted to lock this member in position. This arrangement prevents the stripper from turning too freely in the bushing 17. Up and down adjustment of the 100

stripper may be effected by turning the bushing around and thus causing the stripper to be screwed up and down therein. The punch reaches through a hole in the bottom of the stripper.

If the punch holder 8 should be adjusted without a corresponding adjustment of the stripper being made, and the holder strikes the stripper in consequence, the spring-pressed balls 18 will permit the bushing 17 to be pushed down out of position with the stripper, and none of the parts will be damaged.

Having described our invention, what we claim and desire to secure by Letters Patent is:

1. In a punching machine, a reciprocating punch holder, a work stripper and means for releasably mounting said stripper adjacent to said holder to permit it to be released when engaged by the holder.

2. In a punching machine, a support, a reciprocating punch holder associated with said support, a work stripper releasably attached to said support and adapted to be detached therefrom when struck by said holder.

3. In a punching machine, a support, a reciprocating punch holder associated with said support, a member yieldably attached to said support, and a work stripper attached to said member and adapted to be adjusted by relative rotation of the member and stripper.

4. In a punching machine, a support, a reciprocating punch mechanism mounted on said support, a stripper, means for mounting said stripper adjacent said punch mechanism

said means comprising yieldable members for engaging said stripper to hold it in place but permit it to be detached when struck by the punch mechanism.

5. In a punching machine, a support, a reciprocating punch mechanism mounted on said support, stripping mechanism comprising a threaded member and a stripper having a threaded portion coacting therewith, means for mounting said mechanism on said support comprising yielding members for engaging said member to hold it in place but to release it when struck by any portion of the punch mechanism and means for holding said stripper against rotation whereby it may be adjusted by rotation of said threaded member.

6. In a punching machine, a support, a reciprocating punch mechanism mounted on said support a work stripper and means for impositively securing it on said support adjacent said reciprocating mechanism to permit it to be detached from said support if struck by said mechanism.

7. In a punching machine, a support, a reciprocating punch mechanism mounted thereon, a work stripper and means for impositively securing it on said support adjacent said reciprocating mechanism to permit it to be detached from the support when struck by said mechanism and means for adjusting said stripper with respect to said support.

In testimony whereof we hereto affix our signatures.

GLEN N. HUTCHINSON.
GUY S. CARDEN.
